Alan W. Duncan, Itasca, and Joseph A. Burlini, Morton Grove, Ill., assignors to Sears, Roebuck and Co., Chicago, Ill., a corporation of New York

Filed Apr. 22, 1963, Ser. No. 74,544

Term of patent 14 years

(Cl. D74—9)

Fig. 1.

Fig. 2.

FIG. 1 is a perspective view of a mailbox embodying our new design, and

FIG. 2 is an elevation of the side thereof seen in FIG. 1.

The bottom and back are plain and the side not shown is similar to the side shown in the drawing except that it lacks the signal member and support for same. The top surface is undulating in accordance with the undulations on the top side edge, the knob being positioned at the center of the top.

We claim:

The ornamental design for a mailbox, as shown and described.
